UNITED STATES PATENT OFFICE.

CARNIG NAHABEDIAN, OF NEW YORK, N. Y.

LOCKING-RECEPACLE FOR MILK-BOTTLES.

1,127,076.

Specification of Letters Patent.

Patented Feb. 2, 1915.

Application filed March 28, 1913, Serial No. 757,372. Renewed September 29, 1914. Serial No. 864,190.

To all whom it may concern:

Be it known that I, CARNIG NAHABEDIAN, a citizen of the United States, and a resident of the city of New York, borough of the Bronx, in the county and State of New York, have invented a new and Improved Locking-Receptacle for Milk-Bottles, of which the following is a full, clear, and exact description.

10 Among the principal objects which the present invention has in view are: to provide a receptacle of the character mentioned having a lock which may be operated to release only when removed from the station in which it is placed; to provide a receptacle of the character mentioned, the mechanism whereof is simplified to reduce the cost of construction and avoid disarrangement; and to provide a receptacle having 15 facilities for carrying the bottles in locked position.

One embodiment of the present invention is shown in the accompanying drawings, in which—

20 Figure 1 is a view in perspective, showing in conjunction with fragments of a standing structure, a receptacle constructed and arranged in accordance with the present invention; Fig. 2 is a horizontal section taken on the line 2—2 in Fig. 3; Fig. 3 is a vertical section taken on the line 3—3 in Fig. 2.

25 As seen in the drawings, the receptacle has a rectangular box-like body 8. The body 8 is preferably shallow, and is provided with a solid top 9 and a bottom 10 having a passage opening through one of the sides of the body portion, and terminating at the inner end with a curved edge 11 shaped to conform to the average curvature of the neck of a conventional milk bottle. The open end of the passage is closed when the receptacle is locked, by a closure member having a side flange 12, 30 and an interference member or leaf 13, upon which the said flange is rigidly or integrally formed. It will be understood that when the side flange 12 is closed, the bottle neck or head is held positively within the receptacle or box-like body 8. As hereinafter explained, the leaf 13 and flange 12 connected therewith are locked only when a bottle is placed within the receptacle.

35 The body of the receptacle is provided with a carrying handle or bail 14, which is pivotally mounted in clips 15 on said recep-

tacle. The body is likewise provided at one side thereof with extending flanges 16 and 17. The flanges 16 and 17 are in reality but extensions of the side of the body 8 with 60 which they are connected. The flanges 16 serve as supporting means for the receptacle, being inserted within the grooves formed by the overturned edges 18 of a supporting plate 19. The plate 19 is provided with suitable fastening devices, by means of which it may be permanently mounted upon a door, window shutter, or upon a frame adjacent any opening having a closure member. When the receptacle is 70 placed in service position on the plate 19, the fasteners or screws 20 are concealed and protected.

75 The plate 19 is placed in service position, so that the unobstructed end thereof is adjacent one of the members forming an entrance opening for a standing structure, whether the frame or the closure member thereof is immaterial. That is to say, if the plate 19 is fastened by the screws 20 to the 80 door or window frame, the unobstructed opening of said plate is disposed adjacent the door or window. If, on the other hand, the plate be mounted upon the door or on a casement window, then the unobstructed 85 end of the plate is disposed adjacent the door or window frame. The object in both arrangements is that when the window or door frame opening member is removed from closure position, the unobstructed end 90 of the plate 19 is exposed, to permit the introduction of the flange 16 under the edges 18, or the withdrawal of said flanges and receptacle connected therewith from the support and engagement by the plate 19. 95 The opposite end of said plate 19 is closed by an elongated lug 21. The plate 19 also serves as a closure member for a slot or aperture 22 formed in the back plate or side of the body 8. The aperture 22 is provided to lift a locking bar 23 from engagement with a latch head 24 with which the closure member, or the leaf 13 thereof is provided. The locking bar 23 is pivotally 100 mounted by means of a pin 25, which extends through a guide flange 26 with which said locking bar is provided. The guide flange 26 is housed between plates 27 and 28, the latter having a bracket flange 29 to normally support a horizontal flange 30 105 with which the locking bar 23 is provided. The flange 30, being horizontally disposed

and in a plane parallel with the leaf 13, adds strength to the bar 23 to prevent the closure member having the leaf 13 and flange 12 connected therewith from being forcibly drawn to open position.

At the end of the bar 23, and in juxtaposed relation to the aperture 22, is a pad 31. It will be understood that the neck and head of the bottle for which the receptacle 10 is intended so nearly fill the passage in the bottom 10 of the receptacle as to prevent access to the locking bar 23, it being the design that the sole means for releasing said bar from its engagement with the latch head 15 24 shall be the pad 31. Access to the pad 31 is only possible when the receptacle is removed from the plate 19, and if the plate 19 be secured to the standing structure in service position as above described, it is only 20 possible to remove said receptacle from said plate when the door or window closure is open.

The leaf 13 is pivotally mounted in the body 8 by means of an elongated pin 32. The pin 32 is excessively long to permit the leaf 13 and flange carried thereby to drop out of engagement with the bar 23 when not supported by a bottle held in said receptacle. By this means, provision is made to 30 avoid the annoyance of the accidental or mischievous closing of the receptacle, which, if locked, would prevent the introduction of the bottle to hold which is the purpose of the receptacle. As seen in the drawings, 35 the latch 24 is raised to a position substantially perpendicular to an extension 33 set out from a stop flange 34.

The method of employing and the operation of the receptacle is as follows:—The 40 plate 19 is mounted on the door or window frame by means of the screws 20, and, as above described, with the unobstructed end turned toward the closure member of the door or window opening. The receptacle is 45 then mounted upon the plate 19 by sliding the flanges 16 in the grooves formed by the overturned edges 18, until arrested by the lug 21. When the door or window is now closed, the receptacle is held securely in position, as, in order to remove the same, it becomes necessary to destroy the plate 19 by 50 removing the lug 21 or an overturned edge 18. In this position, the leaf 13 and flange 12 carried thereby are in the lower position 55 shown in Fig. 1 of the drawings, in which position, it will be seen, the latch head 24 passes freely below the bar 23 and in position not to engage said bar. When now, in the course of service, the milkman 60 delivers the milk, he places the bottle under the leaf 13 and lifts it until the lip of the bottle passes above the bottom 10 and into the passage formed therein. To do this, the leaf is raised to the position substantially 65 as shown in Fig. 3 of the drawings, being

supported in position by the lip of the bottle. When now the leaf is swung to such a position as to close the side flange 12 upon the opening in the side of the receptacle, the latch head 24 passes under and lifts the 70 bar 23, to thereafter fall behind said latch head and lock the leaf and flange 12 carried thereby in position. As explained, it is now impossible to gain access to the latch bar 23, which can only be accomplished by removing the window or door opening until the unobstructed end of the plate 19 is exposed to permit the withdrawal of the receptacle and the flanges 16 thereof.

If the receptacle has had placed therein 80 a bottle of the character mentioned, the housemaid or owner may lift the receptacle by means of the handle 14, and safely and conveniently carry the receptacle and body to any desired or convenient station. The 85 bottle may now be released by placing one of the fingers of the hand within the aperture 22 to engage the pad 31 and thereby lift the bar 23 from engagement with the latch head 24. The leaf 13 and flange 12 connected therewith are then free to be swung on the pivot pin 32, to deliver the bottle.

Having thus described my invention, I claim as new and desire to secure by Letters Patent:—

1. A receptacle of the class specified, comprising a box-like body having a side opening, a closure member for said opening, pivotally mounted in said body portion to be raised and lowered relative thereto; a locking member mounted in said body portion to be engaged by said closure member when the same is lifted; means for releasing said lock embodying an opening in the side of said body; a supporting plate for said receptacle having lateral grooves to engage said box-like body; and means for mounting said support on a fixed structure, adjacent a movable member thereof, said member operating to prevent the withdrawal of said body from said plate.

2. A receptacle of the class specified, comprising a box-like body having a side opening; a closure member for said opening, pivotally mounted in said body to be raised and lowered relative thereto; a locking member mounted in said body to be engaged by said closure member when lifted; means embodying an orifice in the side of said body adjacent said locking member to permit the release of the same; a supporting plate for said body, having lateral grooves to engage said body in holding relation and coincidentally to close said orifice; and fastening devices for mounting said supporting plate on a standing structure adjacent a movable closure member of said structure disposable relative to said plate to prevent the withdrawal of the body therefrom.

3. In a receptacle of the character speci- 130

fied, and in combination; a box-like body portion having an end-opening passage the edges whereof are adapted to register with and infold the neck of a bottle, below the 5 lip thereof; a closure member for said passage, embodying a section of the side of said box-like body portion; a leaf rigidly attached to the upper edge of said closure member; an elongated hinge pin to provide 10 for lifting and depressing said closure member; a latch head mounted on said leaf to swing to the inner side of said box-like body portion; and a latch bar pivotally mounted within said box-like body portion to holdingly 15 engage said latch head when said closure member and leaf connected therewith are lifted to pass over a bottle disposed in said passage.

4. In a receptacle of the character specified, and in combination; a box-like body portion having an end-opening passage the edges whereof are adapted to register with and infold the neck of a bottle, below the lip thereof; a closure member for said passage, 20 embodying a section of the side of said box-like body portion; a leaf rigidly attached to the upper edge of said closure member; an elongated hinge pin to provide for lifting and depressing said closure member; a latch 25 head mounted on said leaf to swing to the inner side of said box-like body portion; and a gravity-actuated latch bar pivotally mounted upon one side of said box-like body, adapted to holdingly engage said latch head 30 when said closure member and leaf connected therewith are lifted to extend said leaf above a bottle held in said passage.

5. In a receptacle of the character specified, and in combination; a box-like body portion having an end-opening passage the edges whereof are adapted to register with and infold the neck of a bottle, below the lip thereof; a closure member for said passage, embodying a section of the side of said box-like body portion; a leaf rigidly attached to the upper edge of said closure member; an elongated hinge pin to provide for lifting and depressing said closure member; a latch head mounted on said leaf to swing to the 45 inner side of said box-like body portion; a latch bar pivotally mounted within said box-like body portion to holdingly engage said latch head when said closure member and leaf connected therewith are lifted to pass 50 over a bottle disposed in said passage; means, embodying an orifice in the side of said box-like body portion, adjacent the free end of said latch bar, to admit a finger of an operator to lift said latch bar from engagement with said latch head; and a supporting 55 plate to close said orifice, said plate being covered by the receptacle when mounted in said plate.

60

6. In a receptacle of the character specified, and in combination; a box-like body portion having an end-opening passage the edges whereof are adapted to register with and infold the neck of a bottle, below the lip thereof; a closure member for said passage, embodying a section of the side of said box-like body portion; a leaf rigidly attached to the upper edge of said closure member; an elongated hinge pin to provide for lifting and depressing said closure member; a latch head mounted on said leaf to swing to the inner side of said box-like body portion; a latch bar pivotally mounted within said box-like body portion to holdingly engage said latch head when said closure member and leaf connected therewith are lifted to pass over a bottle disposed in said 80 passage; means, embodying an orifice in the side of said box-like body portion, adjacent the free end of said latch bar, to admit a finger of an operator to lift said latch bar from engagement with said latch head; and a supporting plate to close said orifice, said plate embodying means for holding said body.

7. In a receptacle of the character specified, and in combination; a box-like body portion having an end-opening passage the edges whereof are adapted to register with and infold the neck of a bottle, below the lip thereof; a closure member for said passage, embodying a section of the side of said box-like body portion; a leaf rigidly attached to the upper edge of said closure member; an elongated hinge pin to provide for lifting and depressing said closure member; a latch head mounted on said leaf to swing to the inner side of said box-like body portion; a latch bar pivotally mounted within said box-like body portion to holdingly engage said latch head when said closure member and leaf connected therewith are lifted to 100 pass over a bottle disposed in said passage; means, embodying an orifice in the side of said box-like body portion, adjacent the free end of said latch bar, to admit a finger of an operator to lift said latch bar from engagement with said latch head; a supporting plate to close said orifice, said plate embodying means for holding said body; and devices for fastening said plate to a standing structure, said devices being covered by 105 the receptacle when mounted in said plate.

In testimony whereof I have signed my name to this specification in the presence of two subscribing witnesses.

CARNIG NAHABEDIAN.
